SWAGING TOOL

Harry Bronstein, 1967 71st Ave., Philadelphia, Pa.
Filed May 20, 1959, Ser. No. 814,436
4 Claims. (Cl. 30—11)

The present invention relates to a swaging tool, and more particularly to a swaging tool for attaching a terminal to the end of a cable or the like.

To attach wire cables, such as used on marine craft or aircraft, to each other or to other devices, a terminal is secured to the end of the cable. Such terminals comprise a tubular metal sleeve having an eyelet, hook, or other connecting device at one end thereof. The end of the cable is inserted in the sleeve of the terminal, and the sleeve is swaged around the cable to secure the terminal to the cable. The tools heretofore used for swaging the terminal to the cable are large and cumbersome. Thus, such tools are expensive and difficult to use. Furthermore, such tools require a separate size 20 swaging die set for each size of the terminal to be swaged.

It is an object of the present invention to provide a novel swaging tool.

It is another object of the present invention to provide a novel swaging tool for swaging a terminal onto the end of a wire cable or the like.

It is still another object of the present invention to provide a swaging tool which can be used for swaging various size terminals using a single set of dies.

It is a further object of the present invention to provide a swaging tool which is relatively small in size and easy to use.

Other objects will hereinafter appear.

For the purpose of illustrating the invention there is shown in the drawings a form which is presently preferred; it being understood, however, that this invention is not limited to the precise arrangements and instrumentalities shown.

FIGURE 1 is a front elevational view, partly sectioned, of the swaging tool of the present invention.

FIGURE 2 is a sectional view taken along line 2—2 of FIGURE 1.

FIGURE 3 is a side elevational view of the swaging tool of the present invention.

FIGURE 4 is a sectional view taken along line 4—4 of FIGURE 2.

FIGURE 5 is a sectional view, partly in elevation, of the ratchet mechanism of the swaging tool of the present invention.

Referring initially to FIGURES 2 and 3, the swaging tool of the present invention is generally designated as 10.

Swaging tool 10 comprises a substantially U-shaped body 12 having a base 14 and a pair of substantially parallel arms 16 and 18. Arm 16 has a cylindrical boss 20 projecting from its outer surface, and a recess 22 in its inner surface. Boss 20 has a threaded blind bore 24 in its outer end surface. A rod 26 has a threaded end 28 which is threaded into the bore 24 in the boss 20. Rod 26 has a handle 30 at its outer end, which handle 30 is perpendicular to the threaded end 28.

A pair of identical rollers 32 are mounted in side-by-side parallel relationship in the recess 22 in the arm 16 of body 12. The rollers 32 extend longitudinally between the side walls 34 of the recess 22, and are rotatably supported on separate pins 36. The ends of each of the pins 36 extend through the side walls 34 of the recess 22, and are secured to the side walls 34 by a force fit. Each of the rollers 32 has a cylindrical swaging surface 38 adjacent one end thereof. The surfaces 40 and 42 of each of the rollers 32, which are on oppo-

2

site sides of the swaging surface 38, are tapered inwardly away from the swaging surface 38. The rollers 32 are positioned so that the swaging surfaces 38 of the rollers 32 are spaced slightly apart.

5 A die support 44 extends from the base 14 of the body 12 between the arms 16 and 18 of the body 12. Die support 44 has a pair of spaced arms 46 which embrace the base 14 therebetween. The die support 44 is pivotally supported on the body 12 by a pin 48 which extends through the arms 46 of the die support 44 and the base 14 of the body 12. The surface of the die support 44 which faces the arm 16 of body 12 has a recess 50 therein.

A generally cylindrical die 52 is mounted in the recess 50 in the die support 44, and extends longitudinally between the side walls 54 of the recess 50. Die 52 is rotatably mounted on a pin 56. The ends of pin 56 extend through the side walls 54 of recess 50, and are secured to the side walls 54 by a press fit. Die 52 is positioned with its longitudinal axis substantially midway between the longitudinal axes of the rollers 32. Die 52 has a cylindrical swaging surface 58 adjacent one end thereof. The swaging surface 58 of die 52 is of the same width as the swaging surfaces 38 of rollers 32 but is smaller in diameter. The surfaces 60 and 62 of the die 52, which are on opposite sides of the die swaging surface 58, are tapered radially inwardly away from the die swaging surface 58. Die 52 is divided transversely across the tapered surface into sections 52a and 52b. The juxtaposed end surfaces of the die sections 52a and 52b are provided with matching ball races (not shown). Balls 64 are seated in the matching ball races in the end surfaces of the die sections 52a and 52b so that the die sections 52a and 52b are rotatable

25 with respect to each other. It will be noted that the swaging tool is moved progressively upward on the terminal during the swaging operation. The material of the terminal offers a resistance to this upward movement of the tool and forces the die toward the side wall of the die support 44. If the die contacts the side wall, there is presented undesirable pressure and friction. To overcome this pressure and friction, the die 52 is divided as mentioned above.

35 Arm 18 of body 12 has a flat outer surface 66, and a threaded hole 68 extending through the arm 18 from the flat outer surface 66. A rod 70 has a threaded end portion 72 which is threaded through the hole 68 in arm 18, and engages the die support 44. Rod 70 is in alignment with the rod 26, and both of the rods 26 and 70 are in alignment with the roller swaging surfaces 38 and die swaging surface 58. Rod 70 has a flat surface 74 extending longitudinally along the rod 70 from the threaded end portion 72 of the rod 70. Rod 70 also has an integral handle 76 at its outer end which is perpendicular to the threaded end portion 72.

40 A stop collar 78 surrounds the rod 70 adjacent the arm 18 of body 12. A pair of setscrews 80 are threaded through the stop collar 78, and are adapted to engage the flat surface 74 of rod 70. Stop collar 78 has a central, annular projection 82 extending longitudinally from its end toward the flat surface 66 of arm 18. Surrounding the projection 82, stop collar 78 has a plurality of circumferentially spaced ratchet teeth 83 which project from the end of the stop collar 78 toward the flat surface 66 of arm 18.

45 Arm 18 has a blind hole 84 therein extending from the flat outer surface 66 of the arm 18. An annular plug 86 is threaded in the open end of the blind hole 84. A plunger 88 is within the blind hole 84 and projects through the plug 86 toward the ratchet teeth 82 on the stop collar 78. Plunger 88 has a flange 90

thereon within the hole 84. A helical spring 92 surrounds the plunger 88 within the hole 84, and is compressed between the flange 90 and the bottom of the hole 84. Spring 92 urges the outer end of the plunger 88 toward the ratchet teeth 83 on the stop collar 78. The swaging tool 10 of the present invention is used to swage a terminal onto the end of a wire cable or the like in the following manner:

The swaging tool 10 is first pre-set to the depth of the indentation to be swaged in the terminal. This is accomplished by placing a cylindrical gauge between the rollers 32 and the die 52. The gauge is seated on the two rollers 32 with the gauge extending longitudinally along the rollers 32. A gauge is used which is of a diameter slightly smaller than the internal diameter of the indentation to be swaged into the terminal. The necessity for having the gauge smaller than the diameter of the indentation to be swaged is due to the elasticity of the metal in the terminal and in the swaging tool. The material in the terminal is compressed during the swaging operation and "bounces" back to a small degree after the die is removed or moved upwardly. In addition, there is some elasticity in the die support which must be tolerated. The elasticity in the die support can be eliminated by making the support of stronger and heavier metal, however this is undesirable since it renders the swaging tool too bulky and heavy. The setscrews 80 of stop collar 78 are unthreaded sufficiently to permit the stop collar 78 to bind slightly on the arm 70 and abut the surface 66. With the gauge seated on the rollers 32, rod 70 is threaded inwardly by rotating handle 76 to pivot the die support 44 toward the rollers 32. Rod 70 is threaded inwardly until the swaging surface 58 of die 52 just engages the surface of the gauge. In this position of the swaging tool 10, the gauge is lightly clamped between the swaging surfaces 38 of rollers 32 and the swaging surface 58 of die 52. When the stop collar 78 solidly engages the flat surface 66 of arm 18, the setscrews 80 are threaded in forcibly to engage the flat surface 74 of rod 70 to secure the stop collar 78 to the rod 70. Rod 70 is then threaded outwardly away from the die support 44, and the gauge removed from the swaging tool 10. The swaging tool 10 is now preset and ready for the swaging operation.

For the swaging operation, the end of the cable is inserted into the terminal, and the base end of the terminal is clamped in a vise or similar holding means. The swaging tool 10 is placed around the terminal with the terminal positioned between the rollers 32 and die 52 and extending longitudinally along the rollers 32. The swaging tool 10 is positioned at the terminal end with the swaging surfaces 58 and 38 of the die 52 and rollers 32 being adjacent one end of the terminal.

Rod 70 is then threaded inwardly by rotating handle 76 to move die 52 against the terminal until the terminal is lightly gripped between the swaging surfaces 38 of the rollers 32 and the swaging surface 58 of die 52. At this position of the rod 70, the outer end of the plunger 88 will be in engagement with the ratchet teeth 83 on the stop collar 78.

Grasping handle 30 in one hand and handle 76 in the other hand, handle 76 is rotated to thread rod 70 inwardly further until plunger 88 has clicked over one or two of the ratchet teeth 83 while reverse pressure is exerted on handle 30 to prevent terminal distortion. If reverse pressure were not exerted on handle 30, the pressure of the die swaging surface 58 against the surface of the terminal would have the effect of tending to bend the terminal and not swage the surface thereof. Thus, rotation movement of handle 76 inwardly forces the swaging surface 58 of die 52 to penetrate into the surface of the terminal but not the roller swaging surfaces 38 to any substantial extent because of their greater surface area. The thread on the end portion 72 of rod 70 is of a pitch that each click of the plunger 88 over a ratchet tooth 83

83 indicates that the swaging surface 58 of die 52 has penetrated approximately 0.002 inch into the surface of the terminal. After rotating the handle 76 for one or two clicks of the plunger 88 across the ratchet teeth 83 to force the swaging surface 58 of die 52 into the surface of the terminal, the entire swaging tool 10 is rotated 360° completely around the terminal. This forms an annular indentation in the outer surface of the terminal and compresses the terminal. Upon rotation of the swaging tool 10 around the terminal, the tapered surfaces 42 and 62 of the rollers 32 and die 52 provide a smoothly curved side.

After the swaging tool 10 has been rotated completely around the terminal to initially form the swaged indentation in the terminal, the handle 76 of rod 70 is again rotated until the plunger 88 clicks across one or two more of the ratchet teeth 83. This forces the swaging surface 58 of die 52 further into the surface of the terminal to deepen the swaged indentation. The entire swaging tool 10 is again rotated completely around the terminal to deepen the entire indentation, and further compress the terminal. This step-by-step process of deepening the penetration of the swaging surface 58 of die 52 into the terminal, and rotating the swaging tool 10 around the terminal is continued until the projection 82 on the stop collar 78 engages the flat surface 66 of the arm 18 of body 12. The swaged indentation is then of the pre-set depth to obtain the necessary gripping action between the terminal and the cable. The rod 70 is then threaded outwardly away from the die support 44 to release the swaging tool 10 from the terminal. The swaging tool 10 is then moved along the terminal a distance of approximately one-eighth inch from the swaged indentation, and a second indentation is swaged in the terminal by the step-by-step process previously described. In the same manner, the terminal is swaged to the cable at one-eighth inch intervals along the desired length of the terminal to completely clamp the terminal to the cable.

Thus, there is provided a swaging tool having a single set of dies which can accommodate various sizes of terminals. Any wear of the dies or pins is automatically compensated for since the swaging tool 10 is pre-set for each swaging operation. The swaging tool 10 is relatively small in size and light in weight so that the swaging tool 10 is easy to handle and relatively inexpensive in cost. In the operation of the swaging tool 10, the proper amount of rotation of the rod 70 can be easily determined by feeling or hearing the clicking of the plunger 88 over the ratchet teeth 83. However, if desired, the ratchet teeth 83 may be numbered, and an arrow provided on the arm 18 of the body 12 which points to the ratchet teeth 83. By such means, a visual indication of the degree of rotation of the stop collar 78 with regard to the arm 18 can be obtained.

The present invention may be embodied in other specific forms without departing from the spirit or essential attributes thereof and, accordingly, reference should be made to the appended claims, rather than to the foregoing specification as indicating the scope of the invention.

I claim:

1. A swaging tool comprising a substantially U-shaped body member having a base and a pair of arms, a pair of cylindrical rollers rotatably mounted on the inner surface of one arm of said body member, said rollers being in side-by-side, parallel relation, each of said rollers having a cylindrical swaging surface with said swaging surface being in alignment, a die support extending from the base of said body member between the arms of said body member, said die support being pivotally mounted on the base of said body member for movement toward and away from said rollers, a cylindrical die rotatably mounted on the side of said die support facing said rollers, said die being substantially parallel to but spaced

from said rollers with the longitudinal axis of said die being in a plane extending between said rollers, a cylindrical swaging surface on said die extending across the swaging surfaces of said rollers, and a rod threaded through the other arm of said body member adapted to engage said die support to move said die support toward said rollers, a stop collar surrounding the rod adjacent the outer surface of the other arm of said body member, said stop collar being slideable along said rod, a setscrew threaded through said stop collar to engage said rod and secure said stop collar to said rod at a desired position along said rod, said stop collar having an annular projection extending longitudinally from its end surface facing said other arm of said body member, and ratchet means between said other arm of said body member and stop collar to indicate the degree of rotation of said rod with respect to said body member.

2. A swaging tool in accordance with claim 1 in which said ratchet means comprises a plurality of circumferentially spaced teeth on the end surface of said stop collar which faces the other arm of said body member, a plunger carried by said other arm of said body member, said plunger projecting beyond the outer surface of said other arm of said body member toward said stop collar and adapted to engage the teeth on said stop collar, and spring means urging said plunger toward said teeth on said stop collar.

3. A swaging tool comprising a substantially U-shaped body member having a base and a pair of arms, a rod secured to the outer surface of one of the arms of said body member, a recess in the inner surface of said one arm of said body member, a pair of cylindrical rollers in said recess in side-by-side, parallel relation, each of said rollers being rotatably supported on a separate pin which extends between and is secured to the sides of said recess, each of said rollers having a cylindrical swaging surface with said swaging surfaces being in alignment, a die support extending from the base of said body member between the arms of said body member, said die support being pivotally mounted along the base of said body member for movement toward and away from said rollers, a recess in the side of said die support facing said rollers, a cylindrical die in the recess in said die support, said die being substantially parallel to but spaced from said rollers with the longitudinal axis of said die

being in a plane extending between said rollers, said die being rotatably supported on a pin which extends between and is secured to the sides of the recess in said die support, a cylindrical swaging surface on said die and extending across the swaging surfaces of said rollers, a rod threaded through the other arm of said body member and adapted to engage said die support to move said die support toward said rollers, a separate handle on each of said rods, a stop collar slidably surrounding the rod which is threaded through the other arm of said body member, said stop collar being adjacent the outer surface of said other arm of said body member, a setscrew threaded through said stop collar to engage said rod and secure said stop collar to said rod at a desired position on said rod, said stop collar having an annular projection extending longitudinally from its end surface facing said other arm of said body member, and ratchet means between said other arm of said body member and the stop collar to indicate the degree of rotation of said rod with respect to said body member.

4. A swaging tool in accordance with claim 3 in which said ratchet means comprises a plurality of circumferentially spaced teeth on the end surface of said stop collar which faces the other arm of said body member, a plunger carrier by the other arm of said body member, said plunger projecting beyond the outer surface of the other arm of said body member toward said stop collar and adapted to engage the teeth on said stop collar, and spring means urging said plunger toward said teeth on said stop collar.
